STEREOTYPE PLATE

Curtis S. Crafts, Oak Park, Ill., assignor to The
Goss Printing Press Company, Chicago, Ill., a
corporation of Illinois

Application June 13, 1945, Serial No. 599,229

1 Claim. (Cl. 101—378)

1

The present invention pertains to curved stereotype plates, and more particularly to plates adapted for use in a so-called tension lockup. In such a lockup, the plate is tensioned circumferentially of the print cylinder to hold it in place. For further detail of the locking devices and cylinders used with plates embodying the present invention, reference may conveniently be made to my article entitled "New lockup" published in the March 1945 issue of *Printing Equipment Engineer*, pages 11 to 15.

One object of the present invention is to provide a stereotype plate adapted for use in a tension lockup and which is of a novel construction such as to withstand in a superior manner the severe punishment to which such a plate is subjected during high speed press operation.

Another object is to provide such a plate which is laid out in a manner to minimize shrinks, weak spots or other faults in casting it.

Further objects and advantages of the invention will become apparent as the following description proceeds, taken in connection with the accompanying drawings, in which:

Figure 1 is a perspective view of a curved stereotype plate embodying the present invention.

Fig. 2 is an enlarged fragmentary face view of a portion of the inner or concave face of the plate shown in Fig. 1.

Figs. 3 and 4 are enlarged detail sectional views taken respectively substantially along the lines 3—3 and 4—4 in Fig. 2.

Fig. 5 is a detail sectional view, on even larger scale, taken substantially along the line 5—5 in Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claim.

Referring more particularly to the drawings, I have shown in Fig. 1 a curved stereotype plate embodying the present invention. As is customary in stereotype plates, it is cast from stereotype metal and is of semicylindrical overall shape. On its convex or outer surface is the design or reproduction of type (not shown) which is to be printed.

In the concave or inner face of the plate are two longitudinally extending rows of pockets 10,

2

adjacent the leading and trailing edges of the plate, and in which are received suitable tension fingers (not shown). Such fingers pull the plate tightly and solidly about a printing cylinder to which it is applied, all as more particularly described in my article in *Printing Equipment Engineer* identified above. These pockets 10 are desirably undercut by a slight inclination of their bottom walls 11 (Figs. 3 and 5) to insure a firm grip for the fingers inserted in them. By inclining these bottom walls 10 at a small angle (for example, of the order of 15 degrees) to a plane normal to the vertical medial plane of symmetry of the plate, the pressure of the retaining fingers on the pocket bottoms 10 gives a component of force in a direction such as to pull the plate edges inward and seat them firmly against the cylinder.

The pockets 10 are either cored or milled directly into the body of the plate since the entire concave surface of the latter should preferably be a surface of revolution, free of inward projections, to insure proper seating on the printing cylinder. Such being the case, the plate is of minimum thickness in the portion overlying the pockets. These relatively thin portions of the plate are a source of potential weakness, particularly in view of the heavy loading imposed by the impact of impression.

I have found that the pockets 10 can be adequately reinforced, to withstand even the heavy loads to which the portions of the plate defining them are subjected, by contouring their rear or inner walls 12 in smoothly arched form. As illustrated, the rear walls 12 are arched in all planes 35 of longitudinal section. Such form enables them to withstand a maximum moment of bending.

The arched shape of the pockets 10 is additionally desirable in that it is especially well suited to formation either by coring or milling. 40 In case the pockets are cored out during the original casting of the plate, the rounded or curved shape of the pocket ends prevents formation of blow holes and imperfections in the casting which result if square ends are used. If the pockets are, 45 on the other hand, machined after casting, the illustrated shape is such that they can each be readily cut by a single pass of a rotary form cutter of suitable shape.

The outer edges of the pockets 10 are beveled 50 or relieved as indicated at 14 (see particularly Figs. 4 and 5). This is an important feature for several reasons. Not only does it prevent the throwing up of a burr which would interfere with proper seating of the plate on the cylinder, 55 but in addition the beveling prevents a distortion

of the pocket edges under the high unit pressures developed by the gripping fingers.

The portions of the plate lying between the pockets 10 and the leading and trailing edges of the plate are solid to afford maximum strength in such areas since that is the portion of the plate acted directly upon by the tension fingers. For the sake of simplicity, the entire leading and trailing edge portions 15 of the plate are in this instance made solid from end-to-end of the plate, thus constituting in effect heavy integral bars over which the tensioning fingers inserted in the pockets are hooked.

The concave face of the plate lying between the marginal or bar portions 15 is cored out to define a plurality of parallel circumferentially extending grooves 16. Such grooves are separated by circumferential bearer ribs 17 intersected at intervals by longitudinally extending bearer ribs 18. Both the ribs 17 and 18 are of tapered cross section and have top surfaces which are flat in sectional profile. The top surfaces of the ribs 17, 18 as well as the marginal portions 15 of the plate all lie in a common surface of revolution centered on a longitudinal axis corresponding in location to the axis of the cylinder to which the plate is to be applied. In making the plate, it is preferably interiorly machined to form the top surfaces of the ribs and marginal portions 15, all of which bear directly against the cylinder periphery.

The relative dimensioning of the ribs 17, 18 is of some consequence in minimizing shrink spots during casting. By way of suitable example, of dimensions it may be noted that for a standard $\frac{7}{16}$ inch thick newspaper stereotype plate, the circumferential ribs 17 may be $\frac{1}{8}$ of an inch wide at the top and have flanks or side faces sloped at 45 degrees, the spacing between ribs being approximately $\frac{3}{16}$ of an inch. The longitudinal ribs 18 on the other hand may be spaced at intervals of $22\frac{1}{2}$ degrees and have top faces of a maximum width of $\frac{3}{16}$ of an inch, their flanks also being sloped at 45 degrees.

The ends of the groove 16 are, as indicated at 45

19, sloped gently upward toward the outer faces of the marginal or bar portions 15 of the plate. It is in these sloped end walls or faces 19 of the grooves that the pockets 10 are located, each pocket extending across the ends of a plurality of grooves and intervening ribs 17. Intermediate successive pockets 10 are the end portions of at least one of the ribs 17. By thus, in effect, merging the pockets and ribbing, the liability of shrink spots adjacent the pockets is minimized. In that connection it will be understood that abrupt changes in cross section of the plate always entail a maximum liability of shrinkage difficulties.

I claim as my invention:

15 A curved stereotype printing plate adapted to be tensioned circumferentially about a cylinder, said plate having a plurality of pockets in its concave surface for the reception of gripper fingers, said pockets being arranged in two series 20 adjacent respective leading and trailing edges of the plate, all of said pockets being elongated in the longitudinal direction and having a smoothly arched contour both longitudinally and circumferentially of the plate, said pockets being undercut with the bottom walls of the pockets inclined 25 at a small angle of the order of fifteen degrees with reference to a plane normal to the medial plane of symmetry of the plate, and said plate being solid between the bottoms of said pockets and immediately adjacent portions of its leading and trailing edges.
